UNITED STATES PATENT OFFICE.

FRANK STEWART, OF CHICAGO, ILLINOIS, ASSIGNOR TO THE STOCKHAM MANUFACTURING COMPANY, OF SAME PLACE.

DESIGN FOR A TABLE.

SPECIFICATION forming part of Design No. 31,696, dated October 17, 1899.

Application filed August 1, 1899. Serial No. 725,815. Term of patent 7 years.

To all whom it may concern:

Be it known that I, FRANK STEWART, a citizen of the United States, residing at Chicago, in the county of Cook and State of Illinois, have invented and produced a new and original Design for Tables, of which the following is a specification, reference being had to the accompanying drawings, in which—

Figure 1 illustrates a table of my new design by a perspective view, and Fig. 2 illustrates the same by a plan view.

As shown in the drawings, the leading or material feature of my design consists of the top A, surmounting the bowed legs B. The top has a frame C, of general rectangular shape, with a square center D, representing onyx. In the ornamental open-work composing the frame the four straight sections, which extend at right angles to each other about the center D, are embellished with elongated beads a, terminating at their opposite ends in circular beads b. From each of the four corners formed by these sections there projects outward a perforate fantastic leaf design c, having a heart-shaped lozenge d in its center and a round bead e at its extremity, and these corner-pieces c are con-

nected together along each side of the frame and to the inner beaded sections thereof by the scrollwork f, embellished with a row of beads g, of larger and smaller size, extending lengthwise near the longitudinal center of each side, and with rosettes h on the outer edges of the scrollwork. The legs B, which are disposed at the corners of the top, are of the general S shape illustrated. At the inwardly-bulging sections of the legs they meet the corners of a rectangular shelf E, of ornamental open-work, forming a central square k, with each corner portion i of a design similar to that of the corner portion c of the top D, and the sides about the center k similar in design to the corresponding sides of the top. The fastenings for the shelf are embellished with ornamental heads l.

Having described my invention, what I claim as new, and desire to secure by Letters Patent, is—

The design for a table, as herein shown and described.

FRANK STEWART.

In presence of—

D. W. LEE,

M. J. FROST.
